Milton O. Briggs

Inventor

UNITED STATES PATENT OFFICE.

MILTON OSTRANDER BRIGGS, OF MUSCATINE, IOWA.

WINDOW CURTAIN AND SHADE SUPPORTING BRACKET.

Application filed December 20, 1924. Serial No. 757,231.

To all whom it may concern:

Be it known that I, MILTON OSTRANDER BRIGGS, a citizen of United States, residing at Muscatine, in the county of Muscatine and State of Iowa, have invented certain new and useful Improvements in Window Curtain and Shade Supporting Brackets; and I do hereby declare the following to be a full, clear, and exact description of the invention, such as will enable others skilled in the art to which it appertains to make and use the same.

This invention relates to window curtain and shade fixtures and more particularly to combined curtain rod and shade supporting brackets.

The principal object is to provide a simple, attractive and inexpensive fixture of the character referred to, which may be rigidly secured in place at the top of a window frame by means of a single screw.

A further object is to provide adjustable cooperant brackets for the end and intermediate support of extensible curtain rods with the desired number of shade-rollers over a window frame having two or more casements or sashes.

The invention will first be hereinafter more particularly described with reference to the accompanying drawings, which are to be taken as a part of this specification and then pointed out in the claims at the end of the description.

In said drawings, Fig. 1 is a perspective view of a window frame, showing curtain rods and shade-rollers properly supported in place thereover by means of my improved combination brackets;

Fig. 2 is a perspective view of the right end bracket, showing broken-off portions of the curtain rods secured thereto;

Fig. 3 is a perspective view of the right and left intermediate or mullion brackets; and

Fig. 4 is a perspective view of the left end bracket showing the means by which curtain rod extremities are supportingly secured in place.

Referring to the drawings in which like reference numerals are used to indicate corresponding parts throughout the several views, 5 denotes a window frame having a plurality of casements or sashes with divisional mullions 6.

Ordinary extensible curtain poles or rods

7 and tensioned shade-rollers 8, are rigidly sustained in proper position along the top of the window frame by means of my improved end and intermediate curtain and shade supporting brackets 9 and 10 respectively, the latter being of substantially the same construction as the former, though slightly modified in form to provide intermediate rather than end supports for the curtain rods. Said brackets for purposes of economy, are preferably stamped out of sheet metal and bent angularly to the form shown, although they may if desired, be formed as solid castings.

Referring to Figs. 2 to 4 inclusive, in which the fixtures are illustrated in co-operant relation to each other, the end brackets 9 as shown, are of angular form having vertical main body sections with integral horizontal plate portions 9^a and apertured receiver arms or sleeves 9^b extended laterally from opposite sides thereof at top and bottom respectively, the same being fashioned in reverse corresponding relation for right and left sides of the window frame. Open ended slots or detents 9^c are provided in the upper marginal edge of the main body sections to accommodate either the journal or reeling-pin of a shade roller, and spaced upright pins 85 or keys 9^d are formed or fixed on the outer surfaces of the plate portions 9^a, to provide extremal fastening and support means for curtain rods, although other fastening means may if preferred, be employed.

Adjustable reach-arms or members 11 of angular form, are slidably fitted within the extended sleeves 9^b, said members being slotted to permit single holding screws 12 to be unobtrusively passed therethrough, the latter being inserted through said apertured sleeves, and serving the dual purpose of set-screw and securing means for the brackets in their respective places upon the window frame with the angular members 11 of each bracket in stabilizing complementary contact with the frame moulding as shown in Fig. 1.

The intermediate brackets 10 as shown, are of substantially the same construction as the end brackets above described, the latter being formed with main body sections having integral horizontally projecting arm or ledge portions 10^a and horizontal receiver arms or sleeves 10^b corresponding with 110

the sleeves 9^b of the end brackets 9, extended laterally therefrom at top and bottom respectively, said brackets being fashioned in reverse corresponding relation for 5 right and left sides of the mullions of a window frame. Open ended slots or detents 10^c corresponding with the slots 9^c in said end brackets, are provided in the upper marginal edges of the main body sections to accommodate either the journal or reeling-pin 10^d of a shade roller and spaced similar slots or detents 10^d are provided in the upper marginal edges of the projecting arms or ledges 10^a to receive the curtain rods 7, said arms 15 for such purpose being substituted for the laterally extended plate portions 9^a of the end brackets 9, in order to provide intermediate supports for said rods.

Reach-arms or members 11 and holding screws 12 are also provided for the intermediate brackets which are secured in place upon the mullions of the frame in the same manner as the end brackets.

Having thus described my invention, what 25 I claim as new and desire to secure by Letters Patent of the United States is:

1. A combined curtain-rod and shade-roller supporting bracket of angular form having a main body section with horizontally 30 extended sleeve and article-supporting portions at bottom and top thereof respectively, said body portion being slotted to receive the journal or reeling-pin of a shade-roller and said article-supporting portion being 35 adapted to receive and hold curtain rods, an angular member extensibly fitted in said sleeve and a screw adapted to pass there through for securing the bracket in place upon a window frame with said angular

member in engagement with the moulding 40 thereof.

2. A combined window curtain and shade fixture comprising an angular bracket formed with a main body section having integral horizontally extended sleeve and article-supporting portions, said body section being slotted to receive the journal or reeling-pin of a shade-roller and said article supporting portion being adapted to receive and hold spaced curtain rods, an angular reach-arm extensibly fitted in said sleeve and adapted to stabilizing complementary engagement with the moulding of a window frame, together with a single screw passing through said sleeve and said extensible member for holding the bracket rigidly in place upon a window frame.

3. Combined window curtain-rod and shade-roller supporting brackets of angular form having vertical main body sections 60 with integral horizontally extended sleeve and article-supporting portions, said body sections having open-ended slots for receiving the journals or reeling-pins of shade-rollers and said article-supporting portions being adapted to receive and hold spaced curtain rods, angular members extensibly fitted in said sleeve portions and adapted to stabilizing complementary contact with the moulding of a window frame, together 70 with single screws passing through said sleeve portions and said extensible members for rigidly securing the respective brackets in place with said members in contact with the frame moulding.

In testimony whereof I affix my signature.

MILTON OSTRANDER BRIGGS.
